UNITED STATES PATENT OFFICE.

MOSES G. CARREL, OF CLEVELAND, OHIO.

TICKET.

SPECIFICATION forming part of Letters Patent No. 633,504, dated September 19, 1899.

Application filed March 8, 1897. Serial No. 626,383. (No model.)

To all whom it may concern:

Be it known that I, MOSES G. CARREL, a citizen of the United States, residing at Cleveland, in the county of Cuyahoga and State of Ohio, have invented certain new and useful Improvements in Tickets, of which the following is a full, clear, and exact description, reference being had to the accompanying drawings, forming part of this specification.

10 My invention relates to an improvement in railway-tickets, and comprises, essentially, a sectional ticket the essential characteristics of which lie in making it of separable form and having both sections thereof imprinted 15 with the governing characteristics of the ticket—such as the name of the railway, the conditions under which the ticket is sold, and the railway officer's name and designation—extending across the entire face of the ticket, 20 comprising both sections thereof. In this manner I produce a ticket of such nature that a second use thereof is rendered impossible.

Figure I is a view showing a single-trip 25 ticket embodying my improvement. Fig. II shows a round-trip ticket, each half of which comprises a ticket of the same nature as the single-trip ticket shown in Fig. I.

The essential features of the ticket produced in accordance with my invention are, first, a division-line C, that divides the ticket into sections A and B; second, the name of the road issuing the ticket imprinted across the face thereof, so that part of it is located 35 on one section of the ticket, while the other part is located on the opposite section; third, the arrangement of the name of the station at which the ticket is sold and from which it is good for transportation on one section of 40 the ticket and the destination-station is printed on the opposite section; fourth, the conditions governing the ticket imprinted across the face thereof onto both of its sections; fifth, the arrangement of the signature and designation of the issuing officer extending across the face of the ticket on both 45 sections thereof. With the use of a ticket having these essential features it is imperative that the ticket be intact at the time that 50 it is presented by a passenger to the conductor for transportation, inasmuch as should

the sections A and B, either one, be missing it is incomplete, and this fact is made readily apparent to the conductor by reason of a portion of the wording being absent and indicating clearly without further inspection of the ticket, or, rather, the fragment of it, that it is invalid by reason of not being intact as provided for by the conditions under which the ticket is sold. When the ticket 60 intact is taken up by the conductor, one of the sections is marked "passage-ticket" and the other section is marked "train-check," and these characteristics in the ticket must be presented in order to constitute a valid 65 indication of compensation to the railway company, for if either section is missing the ticket is incomplete, and the absence of a section indicates that the ticket has been mutilated and has therefore become invalid 70 for further use in obtaining transportation privileges.

When the ticket is received by the conductor, the section marked "passage-ticket" is retained by him and is delivered to the auditor of the railway company to serve as a record, and the other section, marked "train-check," is returned to the passenger to serve as an indication of his having compensated 75 the railway company for his transportation. 80

The advantages of this ticket are evident, as material protection is afforded the railway company against improper use of a ticket, as the nature of the ticket produced in accordance with my invention necessitates that it 85 becomes worthless for transportation purposes when the sections are torn apart and the essential features thus canceled by mutilation. It, however, still serves as a record for the auditor of the sale of the ticket and 90 affords the passenger a train-check.

I am aware that a patent was granted to Edwin G. Johnson, May 29, 1877, No. 191,435, for a sectional railway-ticket; but in this ticket a portion of the governing matter there- 95 of was designed to be imprinted on the face of the ticket and the remainder of the governing matter was imprinted on the back of the ticket. This arrangement necessitated the impression of two separate forms, and the 100 entire matter of the ticket was therefore not located in convenient form, as in a ticket

made in accordance with my invention, where the governing features are entirely arranged on the face of the ticket.

I claim as my invention—

- 5 1. A railway-ticket composed of two sections adapted to be separated from each other on a division-line, said ticket having printed on the two sections of the face thereof across the division-line the name of the issuing company, a condition under which the ticket is sold, and the signature with title designation of the issuing officer, and one section containing the name of the station from which passage is accorded and the other section 15 containing the destination-station; substantially as described.

2. A railway-ticket divisible on a given line into a conductor's ticket and train-check, and having the selling and destination points arranged on opposite sides of the dividing-line 20 so as to be borne respectively by the conductor's ticket and the train-check, and a statement of invalidating condition under which it is sold, and the signature with office of issuing agent arranged across said line, so as 25 to be divided by the separation of the ticket and check, thereby to cancel the same and invalidate each part as a ticket.

MOSES G. CARREL.
